CLAIM

The ornamental design for a compact camera, as shown and described.

DESCRIPTION

FIG. 1 is a front, top and side perspective view of a compact camera showing my new design, with a lens cover thereof in the open position;

FIG. 2 is a front elevational view thereof;

FIG. 3 is a rear elevational view thereof;

FIG. 4 is a top plan view thereof;

FIG. 5 is a bottom plan view thereof;

FIG. 6 is an end elevational view thereof from the left of FIG. 2;

FIG. 7 is an end elevational view thereof from the right of FIG. 2; and,

FIG. 8 is a view similar to FIG. 2 but with the lens cover thereof in a closed position.
